US0D1043244S

(12) **United States Design Patent** (10) Patent No.: **US D1,043,244 S**
(45) Date of Patent: ** Sep. 24, 2024

(54) **AIR FRYER BASKET**

(71) Applicant: **WHIRLPOOL CORPORATION**,
Benton Harbor, MI (US)

(72) Inventors: **Tushar A. Kalbande**, Pune (IN);
Jessica Lea Kormanik, St. Joseph, MI
(US)

(73) Assignee: **WHIRLPOOL CORPORATION**,
Benton Harbor, MI (US)

(**) Term: **15 Years**

(21) Appl. No.: **29/925,641**

(22) Filed: **Jan. 25, 2024**

Related U.S. Application Data

(63) Continuation of application No. 29/841,157, filed on
Jun. 3, 2022, now Pat. No. Des. 1,017,320.
